UNITED STATES PATENT OFFICE.

ENNO HENRY AUGUST HABBERT, OF TROY, NEW YORK.

SEAM STRUCTURE FOR COLLARS AND CUFFS.

Application filed April 13, 1921. Serial No. 460,901.

To all whom it may concern:

Be it known that I, ENNO HENRY AUGUST HABBERT, a citizen of the United States of America, residing at Troy, in the county of

5 Rensselaer and State of New York, have invented certain new and useful Improvements in Seam Structures for Collars and Cuffs, of which the following is a specification.

This invention relates to a process, more 10 particularly adapted for use in the construction of collars and cuffs and directed to securing the raw edge of one or more plies of material by turning the edge any desired depth and so stitching the turned edge as 15 to completely or substantially cover the raw edge, and at the same time forming a bead-like projection on the surface of the collar or cuff thru the tension of the stitches covering the raw edge.

20 This invention is also directed to the article produced by the improved method including the raw edge finishing means and the bead produced thereby.

The former method of disposing of the 25 raw edges of the various plies of the material making up the collar and cuff is satisfactory in its results but comparatively expensive to carry out, while the present method as described in this application is 30 equally satisfactory in its results and materially less expensive to carry out. A distinct advantage of and a material part of the method herein described is directly incident to the tension of the raw edge covering 35 threads, as by an appropriate tension the material on the face of the collar or cuff may be given a bead effect, heretofore secured by the insertion of a cord. The bead effect produced by this invention may be 40 varied as desired, merely by a variation in tension of the thread referred to, and hence the process, generally stated, involves the use of stitches produced in a well known manner for the laying in and covering of 45 the raw edge of a folded edge fabric in one or more plies, with an additional and desirable effect produced solely by the tension of such laying in and covering stitches.

The process can be readily understood 50 from the accompanying drawings, in which:—

Fig. 1 is a broken plan of a collar edge illustrating the invention.

Fig. 2 is a plan of the face or reverse 55 side of the same showing the cord effect.

Fig. 3 is a materially enlarged transverse

section through the edge, to illustrate particularly the method of laying in the raw edge and simultaneously producing the cord effect. 60

The invention is illustrated, and as herein-after specifically described, is applied more particularly to a collar, though it is to be specifically understood that no limitation of the application of the process is to be 65 indicated thereby, as many other articles of manufacture are adapted for the use of the process with equal commercial results.

As shown, the collar edge 1, including one or several plies, is turned at 2 and the raw 70 edge 3 of the several plies laid against one surface of the collar proper. This edge is then secured by the improved process which consists in passing parallel rows of stitching 4 and 5 thru the material, one of such rows 75 passing thru the collar and turned edge adjacent to but inwardly of the raw edge 3. The other row of stitching 5 passes thru the material adjacent to but beyond and free of the raw edge 3. These rows of stitching 80 4 and 5 are united by a single under thread 6, which under thread, as a result of the disposition of the rows of stitching 4 and 5, directly overlies and substantially covers 85 the raw edge 3. 85

If it is desired, and as contemplated, as an essential step in the process, a bead or simulated cord formation may be given the face side of the fabric, as is usually provided in collars, cuffs and like articles. 90 With the present process, this bead or simulated cord formation is secured by the tension of the under thread stitching 6 as in accordance with the tension of such stitching 6, the material on the face side of the 95 article between the rows of stitching 4 and 5 may be caused to protrude beyond the surface in a rounded bead-like formation, as at 7. The extent, that is, the projective dimension of this bead-like formation is 100 readily regulated, within limits, by the degree of tension of such under thread stitching 6, as will be perfectly obvious.

It will of course be understood that the 105 various rows of stitching 4, 5, and 6, are readily produced with a multiple needle sewing machine employing one under thread.

Characteristically, the improved process consists essentially in a method of stitching whereby the raw edge of the one or several 110 plies at the turned edge of an article may be laid in, effectively secured, and prac-

tically covered by certain of the stitches; the process also including as an important detail, the provision of a bead or cord effect on the face of the article by the tension of the 5 thread forming the stitches which are adapted to cover the raw edge.

An advantage of this particular cord effect when used is that it is formed wholly from the material itself and hence there is 10 practically no liability of crinkling, nor is there any obstacle to the turn of a short rounded corner though both of these disadvantages are well known objections to the use of the usual cord for producing this 15 effect.

It will be apparent to those skilled in the manufacture of collars and cuffs, that the present invention, while producing an article fully as perfect in service and appearance 20 as the articles produced under previous methods, is materially less expensive than such previous methods, and hence a material commercial advantage.

The present invention contemplates the 25 article produced by the method herein described, and such article will be claimed as a part of the invention.

Claims:

1. The herein described method of securing the raw edge of a folded-edge fabric article, consisting in applying a plurality of 30 rows of stitching to the fabric inwardly of and substantially parallel with the folded edge, one at least of which rows of stitching 35 does not pass thru the raw edge, and uniting said rows of stitching on the folded edge side of the fabric only by transverse threads which overlie and substantially cover the raw edge.

40 2. The herein described method of securing the raw edge of a folded-edge fabric article, consisting in applying a row of stitching thru the fabric and folded edge, a second row of stitching thru the fabric inwardly of and free of the raw edge, and uniting said rows of stitching by transverse threads on the folded edge side of the fabric only, whereby said transverse threads overlie and confine the raw edge of the folded 45 edge portion.

50 3. The herein described method of securing the raw edge of a folded-edge fabric article, consisting in applying a row of stitching thru the fabric and folded edge, a second row of stitching thru the fabric inwardly of and free of the raw edge, and uniting said rows of stitching by transverse threads on the folded edge side of the fabric only, said transverse threads being tensioned to form 55 a bead effect in the fabric between said rows of stitching.

60 4. The herein described method of securing the raw edge of a folded-edge fabric article, consisting in applying a row of stitching thru the fabric and folded edge, a

second row of stitching thru the fabric inwardly of and free of the raw edge and uniting said rows of stitching by transverse threads on the folded edge side of the fabric only, said transverse threads being tensioned 70 to form a bead effect in the fabric between and transversely co-extensive with said rows of stitching, the raw edge of the folded edge being confined in the hollow of said bead by the transverse threads. 75

5. The herein described method of securing the raw edge of a folded-edge fabric article, consisting in simultaneously applying two spaced rows of stitching thru the fabric and folded edge lengthwise said edge, 80 one of said rows of stitching passing thru the fabric and folded edge, and the second of said rows of stitching passing thru the fabric inwardly of and free of the raw edge of such folded edge, and uniting said rows 85 of stitching on the folded edge side of the fabric only by cross threads, the said cross threads overlying the raw edge portion only of the folded edge and providing a substantially complete covering for such raw edge, 90 the absence of thread formation between said rows of stitching on the side of the article opposite the raw edge permitting a tensioning of the cross threads to form a bead outwardly of the plain side of the article between said rows of stitching. 95

6. The herein described method in a collar or cuff of providing means for securing the raw edge of a folded edge of such article and presenting at the same time a substantially 100 smooth surface on the folded edge side of the article, consisting in applying a row of stitches through the folded edge and through the opposite surface of the article, a second row of stitches through the fabric inwardly 105 of and wholly free from the folded edge and uniting the stitches of each of said rows by transverse threads which overlie and confine the folded edge throughout the full width between said first mentioned rows of stitching, the transverse threads binding the raw 110 edge of the folded edge onto the article and substantially covering said raw edge to present a substantially smooth surface on the folded edge side of the article. 115

7. The herein described method of securing two or more plies of a collar or cuff to present a substantially smooth surface at the juncture, consisting in folding the similar edges of the plies loosely onto one side of the 120 article, securing said folded edge by a row of stitching extending through the article and through said folded edge, applying a second row of stitching substantially parallel to the first and passing through the article wholly 125 free of the folded edge, and uniting the stitches of said rows of stitching by transverse threads which completely overlie the folded edge throughout a material portion of its width and completely overlie and sub- 130

stantially cover the raw edge of said folded edge.

8. The herein described method of securing two or more plies of a collar or cuff to present a substantially smooth surface at the juncture, consisting in folding the similar edges of the plies loosely onto one side of the article, securing said folded edge by a row of stitching extending through the article and through said folded edge, applying a second row of stitching substantially parallel to the first and passing through the article wholly free of the folded edge, and uniting the stitches of said rows of stitching by transverse threads which completely overlie the folded edge throughout a material portion of its width and completely overlie and substantially cover the raw edge of said folded edge, said transverse threads being so tensioned as to bind the raw edge of the folded edge into contact with the adjacent surface of the fabric

to avoid obstruction of such raw edge of an otherwise substantially smooth surface.

9. A collar or cuff having the edge portions of superimposed plies folded over on one surface to produce a finished edge of the article, means for securing said folded edge to the surface over which it lies to provide a substantially smooth juncture over said folded edge and surface, said means comprising rows of stitching passing through the plies with one of said rows of stitching passing through said folded edge and the other of said rows of stitching being arranged beyond said folded edge, and cross threads uniting the stitching of said rows and overlying and confining said folded edge, whereby to render that surface of the article receiving the folded edge substantially smooth and unbroken.

In testimony whereof I affix my signature.

ENNO HENRY AUGUST HABBERT.
